UNITED STATES PATENT OFFICE.

ORIN C. FENLASON, OF RAYMOND, WASHINGTON.

COLLAPSIBLE VENEER BERRY-BOX.

1,298,921.

Specification of Letters Patent.

Patented Apr. 1, 1919.

Application filed May 8, 1917. Serial No. 167,177.

To all whom it may concern:

Be it known that I, ORIN C. FENLASON, a citizen of the United States, residing at Raymond, in the county of Pacific and State 5 of Washington, have invented a new and useful Collapsible Veneer Berry-Box, of which the following is a specification.

This invention relates to collapsible veneer berry boxes.

10 The object is to provide a box for holding berries, fruit, or the like, which is designed to be formed of ordinary stock wood veneer, and which, when empty, is capable of being collapsed and compactly folded into a thin 15 package and thus, when packed into bundles, may be shipped in great quantities at reduced cost of transportation.

Another object is to construct a box of this character having a minimum number 20 of parts and fastening means therefor, and to so fashion the component strips of veneer that they may be formed, scored, slitted and otherwise treated without necessitating an undue number of separate operations.

25 A further object is to improve the construction of this class of boxes so as to provide one which is capable of being set up by a simple operation, and which may be as readily collapsed and folded to occupy 30 a minimum amount of space.

A full and complete understanding of the invention may be obtained from a careful consideration of the following detailed description, taken in connection with the accompanying drawings forming a part of 35 this specification; it being understood that while the drawings show a practical form of the invention, the latter is not confined to strict conformity therewith, but may be 40 changed or modified, so long as such changes or modifications mark no material departure from the salient features of the invention, as specifically pointed out in the claim appended hereto.

45 In the drawings, in which like reference numerals designate corresponding parts in each of the several figures:—

Figure 1 is a perspective view of one form of the invention in a set up condition.

50 Fig. 2 is an end elevation of the same viewed from the opposite direction to Fig. 1.

Fig. 3 is a vertical sectional view taken on the line 3—3 of Fig. 2.

55 Fig. 4 is a detail perspective view of the bottom member detached from the walls of the box.

Fig. 5 is a perspective view of a modified form of the improved berry box in set up condition.

Fig. 6 is a detail perspective view of the bottom member shown in the form illustrated in Fig. 5.

Referring to the drawings, there is shown in Fig. 1 what may be considered the preferred form of the invention, wherein a 65 complete box for berries, fruit, or the like, is formed of but two members or parts, one of which comprises the sides or body of the box, and the other the bottom therefor, the two parts being securely fastened together 70 by the use of but three staples or other fastening devices, and so arranged as to permit of the disengagement of certain interlocking means, to be described, and to allow of folding the two members into a flat pack- 75 age for bundling purposes.

In order to accomplish these ends, the body member comprising the sides of the box is composed of a strip 1 of ordinary stock veneer of a width equal to the desired 80 height of the box, and this width may vary in accordance with the predetermined capacity of the same.

The strip 1 is of a length sufficient to form the four sides of the box and to provide for 85 a terminal flap 2 at one end thereof, the said strip being provided with lateral scores 3 arranged equi-distantly apart and adapted to permit of bending along these lines to form the corners or angles of the box, the 90 panels 4, 5, 6 and 7, thus formed, comprising the sides of the same.

The terminal flap 2 is adapted to lie on the outside of the adjacent side panel 4 and to be secured thereto by upper and lower 95 staples or other fasteners 8 and 9, and is of a length sufficient to reach substantially half way across the said panel 4. A rectangular body member is thus formed, capable of being bent into the form of a square box 100 or of being collapsed into a relatively long flat formation.

The side panel 6 which is arranged diametrically opposite to the first panel 4 and terminal flap 2 is provided with upper 105 and lower longitudinally disposed slits 10 and 11, extending throughout the length of the panel and spaced a considerable distance from the top and bottom edges of the said panel 6, so as to provide three independent 110 longitudinal strips therein of sufficient width to withstand the strain, at these points

of juncture with the adjacent side panels 5 and 7, incident to the application of certain parts to be interlocked therewith, as will be hereinafter described.

- 5 The slits 10 and 11 pass entirely through the panel 6, no material whatsoever being removed thereby, from the sheet of veneer, and thus the slits may readily be formed at the same time and by the same machine 70
- 10 that is used to cut the body member 1 from a sheet of veneer, without any liability of splitting the veneer. By reason of this, the slitting of the body member does not necessitate a separate operation which would add 75
- 15 to the cost of manufacture. The scoring of the body member to form the angles or corners of the box is performed after the body member has been cut out and slitted as described.
- 20 The bottom member 12 of the box is formed of a strip of veneer somewhat less in width than the length of the side panels of the box so as to provide ventilating spaces on each side thereof for the purpose of allowing the free passage of air through the 80 contents of the box.
- The bottom 12 is suitably scored to provide terminal flaps 13 and 14, the flap 14 being bent to an upstanding position and 85
- 30 adapted to lie on the inner side of the side panel 4 and to be secured thereto, adjacent one side edge of the aforementioned staple 8 and an additional staple 15 arranged adjacent the other side edge of the flap 14 and, 90
- 35 like the staple 8, near the top edge of the side panel 4. The opposite terminal flap 13 of the bottom member 12 is tapered along its side edges, and is provided, at an intermediate point of its juncture with the bottom 95
- 40 12, with a depending pointed or V-shaped tongue 16, formed integral therewith and adapted to lie, at all times, in a plane with the said flap.

The tongue 16 is formed by cutting or slitting entirely through the bottom member 12 inwardly from the score line, the scoring extending from the side edges of the bottom member at the point of juncture with the flap, up to but not across the said tongue, as 100

45 clearly shown in Fig. 4 of the drawings.

The flap 13 is adapted to lie within the central strip of the side wall 6 and to pass upwardly and outwardly through the upper slit 10 and to lie, at its upper extremity, on 105

50 the outer face of the upper strip of the wall 6.

By elevating the bottom member 12, it will be seen that the downwardly extending tongue 16 may, by reason of its pointed 110

60 lower end, be readily introduced into the lower slit 11 of the side wall 6, so as to lie on the outer face of the lower strip of said side and prevent the bottom from being depressed out of a horizontal position, by reason 115

65 of the top edge of the lower strip of the

side wall being drawn thereby beneath the adjacent outer edge of the bottom.

In this manner the bottom of the box is supported at each end in spaced relation to the lower edges of the side walls, thus providing an air space beneath the same for the purpose of ventilating the fruit or other perishable commodity contained therein. 120

A somewhat modified form of the invention is illustrated in Figs. 5 and 6 of the drawings, wherein a body member, 1^a similar to that already described is used, having the side panels 4, 5, 6 and 7. In this form of the device the oppositely disposed side walls 5 and 7 are simultaneously slitted at the time 80 the body member 1 is cut from the sheet of veneer in a manner similar to the first described form of the invention. These slits 10^a and 11^a are adapted to receive the end flaps 17 and 18 of a bottom member 19 and 85

to support the same in spaced relation to the bottom of the box, as heretofore described, the end flaps being each provided with a pair of pointed tongues 17^a and 18^a, respectively, 90

adapted to engage and interlock with the lower slits 11^a, 11^a to prevent the downward movement of the bottom 19.

In the last described form of the invention, it will be seen that only two fastening devices 20 are necessary to hold the body 95 member 1^a together, and furthermore that the bottom member 19 may be entirely detached therefrom, by simply raising the same until the tongues 17^a and 18^a are disengaged from their respective slits when the 100 same may be removed, packed together in bundles and shipped separately from the body members, thus effecting a great saving in space and a consequent saving in cost of transportation. 105

By reason of the fact that slits are provided in the body, it is essential in assembling the box that the flaps should be readily passed through the slits. The tapering sides of the flaps, in connection with the tapered 110 or V-shaped tongues, enable the flaps and tongues to be quickly passed through the slits, and the box easily set up. In applying the bottom member, the flap is first passed through the upper slit and then the tongue 115 is entered through the lower slit.

What is claimed is:

A veneer box comprising a body member scored transversely at intervals to form the corners of the box, said body member constituting the sides thereof and having the ends of the member overlapped and stitched together, said body member having a pair of parallel longitudinal slits spaced apart in the direction of the height of the box, 125 each slit having a length corresponding to one of the side walls of the box and extending from one score line to the other, with no portion of the box removed when forming the slits, whereby said slits are made at the 130

same time and by the same machine that is used to cut the body member from the sheet of veneer, and a separate bottom member scored transversely to form end flaps, one 5 of said flaps having tapered sides to pass through the top slit and lie on the outside of the side wall above said slit with its end edge substantially flush with the upper edge of said side wall, and a V-shaped tongue cut 10 from the bottom member and having its base located at the juncture of the flap and bottom, said tongue being passed through the bottom slit so as to engage the outer face of the side wall and cause the bottom member to rest upon the bottom wall of the slit on 15 each side of the tongue.

In testimony, that I claim the foregoing as my own, I have hereto affixed my signature in the presence of two witnesses.

ORIN C. FENLASON.
